Attorney

UNITED STATES PATENT OFFICE.

JOHN J. KUNTZ, OF BROOKLYN, NEW YORK.

SAFETY APPLIANCE FOR ELEVATORS.

1,182,914.

Specification of Letters Patent.

Patented May 16, 1916.

Application filed July 9, 1914. Serial No. 850,049.

To all whom it may concern:

Be it known that I, JOHN J. KUNTZ, a citizen of the United States, residing at Brooklyn, in the county of Kings and State 5 of New York, have invented certain new and useful Improvements in Safety Appliances for Elevators, of which the following is a full, clear, and exact specification.

This invention relates to safety appliances 10 for elevators, and has for its object to provide improved means for automatically breaking the circuit to the controller of an electric elevator whenever one of the doors to the shaft is left open or unlocked.

15 A special object is to improve the construction of the circuit breaker used in connection with each of the doors leading to the elevator shaft, which circuit breaker will automatically break the circuit to the controller when its door is opened and will not close the circuit again until the door is fully closed and locked.

The invention will be first hereinafter described in connection with the accompanying 25 drawings, which constitute a part of this specification, and then more specifically defined in the claims at the end of the specification.

In the accompanying drawings, wherein 30 corresponding parts are indicated by similar reference characters throughout the several views: Figure 1 is a diagrammatic view of an elevator shaft with three doors, the middle one of which is open disclosing the controller 35 on the elevator arranged opposite said door, and indicating the circuit from a generator including my improved circuit breakers as well as the controller. Fig. 2 is an interior side view of one of my improved circuit 40 breakers, and Fig. 3 is a cross section through Fig. 2 with the circuit closer in open position.

In Fig. 1, A, A' and A² designate the doors to an elevator shaft B, and C indicates the controller on the elevator which, as shown, is arranged opposite the open door A'. D, D' and D² designate my improved circuit breakers applied to the frame of each of the doors. Each circuit breaker has 45 a spring leaf E which is pressed inward so as to close the circuit when the door is closed and locked, but which automatically springs outward and breaks the circuit when released by the unlocking and opening of the 50 door. The circuit from the generator F is through conductor G which includes the

motor G' to the top one of the circuit breakers, by conductor H from this circuit breaker to the next one, by conductor I from the second circuit breaker to a fixed point c, 60 by looped conductor J from the fixed point c to the controller, by looped conductor J' from the controller to a fixed point c', by conductor I' from the point c' to the third circuit breaker, and by conductor K from 65 the third circuit breaker back to the generator.

It will thus be seen that when anyone of the doors is left unlocked, the corresponding circuit breaker will automatically interrupt the circuit to the controller and prevent the car from being moved until said door has been closed and locked. It will be understood that when the door is closed, it engages the projecting spring leaf E and depresses the same to close the circuit. If the door is not locked or screwed, however, the resiliency of the leaf will force the door open again far enough to break the circuit. In other words, it is necessary to lock or secure the door in closed position in order to maintain a closed circuit. Consequently, all danger from accidents due to elevator doors being left unlocked are effectually avoided. 80

Referring to Figs. 2 and 3, within the 85 casing of each circuit breaker there is a partition L to which the terminal contacts M, M' are secured in spaced relation. Intermediate of said contacts, the partition is perforated, as at N. The spring leaf E is 90 secured at one end to the outer surface of the casing and is normally pressed outward by a spring O coiled about a guide pin P which is secured to said leaf near its attached end and extends through the wall of the casing 95 and also through the partition L, see Fig. 2. The spring O abuts at one end against the partition and at the other end against a nut Q which is adjustable on the pin P for the purpose of varying the tension of the 100 spring. The pin P is provided with a head R, or other obstruction on the opposite side of the partition from the spring, for limiting the outward movement of said pin and the leaf E. 105

Attached to the leaf E near its free end is a guide pin S extending into the casing and carrying at its inner end a bridging plate T normally arranged opposite but out of contact with the terminals M and M'. 110 The bridging plate T is adapted to slide along the guide pin S against the influence

2. of a spring U for equalizing the pressure of said plate upon both terminals when the leaf E is pressed in. The spring U may be coiled about the pin S so as to abut at one 5 end against the plate for normally holding the same against the head V at the inner end of said pin, while the other end of said spring abuts against a washer W fixed to the pin in any suitable manner.
10. As indicated in dotted lines in Fig. 2, when the leaf E is pressed in, the bridging plate T will first come in contact with the terminals M and M' and then be forcibly held with equal pressure against both of said terminals 15 by the contraction of the spring U as the leaf reaches its fully pressed in position. In this last stage of the movement of the leaf, the inner end of the pin S is projected into the opening in the partition. The 20 inner end of the pin P is projected slightly beyond the partition L by the inward movement of the leaf E, the spring O being thus contracted and its tension consequently increased so that it will automatically move 25 the leaf outward again to break the circuit as soon as said leaf is released by the unlocking of the door to the elevator shaft.
- Having thus described my invention, what I claim as new and desire to secure by Letters Patent of the United States is:
30. 1. A circuit breaker comprising a casing,
- a partition therein, a pair of spaced terminals secured to said partition, a spring pressed leaf, a guiding pin carried by said leaf, a bridging plate mounted to slide along said pin, and resilient means for yieldingly holding said plate at the inner end of the pin, said plate being adapted to engage the terminals before the leaf is fully depressed, and said partition having a recess between 35 the terminals for receiving the end of the pin when projected beyond the plate on the full inward movement of the leaf.
2. A circuit breaker comprising a casing, 40 a partition therein, a pair of spaced terminals, a bridging plate carried by the leaf and adapted to engage said terminals when the leaf is depressed, a pin carried by the leaf and extending through the partition, a projection on the inner end of said pin for 45 limiting the outward movement of the leaf, an axially adjustable nut on said pin, and a spring interposed between said nut and the partition for the purpose specified.
- II. testimony whereof I have signed my 50 name to this specification in the presence of two attesting witnesses.

JOHN J. KUNTZ.
